UNITED STATES PATENT OFFICE.

GEORGE HOLT FRASER, OF BROOKLYN, NEW YORK.

SEPARATOR.

Original application filed August 28, 1914, Serial No. 859,004. Divided and this application filed June 28, 1919. Serial No. 307,417. Renewed April 3, 1924.

To all whom it may concern:

Be it known that I, GEORGE HOLT FRASER, a citizen of the United States, residing at No. 226 Quincy Street, in the borough of Brooklyn, county of Kings, city and State of New York, United States of America, manufacturer, have invented certain new and useful Improvements in Separators, being a division of my original application filed August 28, 1914, Serial Number 859,004, renewed December 18, 1918, Serial Number 267,402, of which the following is a specification.

This invention relates to apparatus for separating, sizing or classifying materials by means of a fluid current, and aims to provide certain improvements therein.

Heretofore it has been common to separate fine from coarse material by an air current, by passing the material through a casing in which a revolving blower created a current for floating the fine material out and depositing it in a dust chamber, after which the current was returned to the inner side of the falling material and again passed through it.

Attempts have been made to prevent coarse particles from being carried out with the fine, and to ensure a uniform separation.

This invention relates to separators in which classification of the product is aimed at, and the invention aims to provide improvements whereby the product may be selected with greater certainty, or the material may be classified and separated into several grades.

The invention aims to provide an improved separator which will more certainly ensure the absence of coarse material in the fine product, and which can be used to make several grades of material of different degrees of fineness if desired.

To this end in carrying out the preferred form of the present improvements, the pulverized or other material to be treated is fed into the separator in an annular descending stream through which the current is drawn outwardly to float out the desired fines, a blower is provided outwardly of this stream, and surrounding the descending stream of material annular selecting or classifying means are employed, preferably between the stream and the blower and outwardly of the blower. The descending ma-

terial is preferably fed into the separator and dropped downwardly between reverse annular distributing and collecting rings, which alternately spread and concentrate it, as well as retard its speed of descent. Outwardly of these are concentric annular passages of varying elevation so as to give an annular wave effect to the outflowing current. Downwardly directed deflectors encircling these passages vary the direction of the current to produce wave effects therein, and the dust carried by the current is subjected to circuitous travel and centrifugal action as the current winds past these deflectors, facilitating separation of the heavier particles from those light enough to float in the current despite its circuitous progress. Annular collecting troughs for the over-size particles thus separated from the outwardly traveling current, are provided between the distributing rings and the blower, and collecting and return passages are provided for this intermediate product. Preferably a series of such deflectors, passages and troughs is disposed between the feeding rings and the blower.

Beyond the selectors is a blower chamber from which through a contracting outlet the dust-laden current is projected at high speed downwardly into a large settling chamber, from which it is withdrawn in direction transverse to its introduction and at relatively low speed through a return passage, and again carried to within the falling mass of material, so that the same current is continuously used to float out the fines.

In the accompanying drawings, Fig. 1 is a vertical axial section of an air separator embodying the preferred form of the present invention, and Fig. 2 is a fragmentary horizontal section of the foraminous wall, in connection with which this form will be described in detail.

Referring to the drawings, let A indicate a casing, B the driving mechanism, C the feed hopper, D the distributor, E the feed chamber, F the blower, G the dust chamber, H the return passage, I the coarse outlet, and J the fine outlet, all of which parts may be of any usual or suitable construction.

The casing A consists of a cylindrical body a, a top b, and a conical bottom c carrying a casting d in which are formed the coarse and fine outlets.

The driving mechanism comprises a tubu-

lar shaft K mounted in upper and lower bearings e in a bracket f which supports the separator. The shaft K has an upper shoulder g on which rests a bevel gear h meshing 5 with a similar gear i carried by a shaft j which is driven from fast and loose pulleys k and l. The shaft K has a lower shoulder m resting on a split collar n which is supported by a ball bearing o resting on the 10 bracket f near the lower end of the shaft.

The shaft K extends into the casing A and is separably connected to the head L of the blower, which it revolves.

The hopper C is movably and adjustably 15 carried on a shelf p of the bracket f, having a flange q resting on this shelf, and a feed inlet r coinciding with and discharging feed into an adjustable feed tube M which is slidingly fitted to the hopper so that it can 20 be raised or lowered toward the distributor disk to regulate the speed of feed to the latter. The feed tube M passes freely through the drive tube so that the latter can rotate independently of it.

25 The distributor D is a revolving disk suspended from the fan head L, and is revolved with sufficient rapidity to throw off the material radially within the casing.

Surrounding the edge of the feed tube 30 is a baffle ring or deflector N which deflects the incoming feed downwardly in an annular stream surrounding the suction chamber O of the separator. Beneath the disk D is an annular distributing ring P which 35 distributes outwardly any material falling from the disk and not striking the deflector N. Below these are a series of collecting rings Q and a series of inner distributing rings R arranged in succession so that the 40 descending material falling onto the ring Q slides down the latter and is concentrated and discharged therefrom onto the distributing ring R, from which it is outwardly deflected and falls onto the next ring Q, from 45 which it is again carried to the next ring R, by which it is again deflected and distributed onto the lower ring S, from which it falls to the coarse cone T. Above each ring Q is an annular upwardly extending 50 current passage U through which the current traversing the falling material rises to pass over the adjacent collecting ring. Above this passage is a downwardly extending deflector ring V against which the rising current impinges, and by which it is deflected downwardly, so that it may pass outwardly under the lower edge thereof. Beneath each deflector is an annular selecting trough or space W having a bottom out- 55 let for precipitating downwardly any coarse material deposited in the trough. The outer side of the trough is formed by an annular deflecting ring X, which reverses the descending current from the deflector V and 60 directs it upwardly over the top edge of the 65

adjacent ring X, over which it flows to the inner side of the blades s of the blower F. The series of blades opposite the outlet from each trough is isolated by a partition t from those opposite the adjacent outlet, so that variations of current through the different outlets cannot equalize and their uniform suction is maintained opposite each. 70

The blades of the blower are preferably 75 in the form of a barrel or cylindrical fan, revolving around the distributing and selecting disks.

Preferably outwardly of these blades is an 80 annular trough Z, the inner wall of which consists of a downwardly extending deflector Y and the outer wall of which consists of an upwardly extending deflector A¹, which directs the outgoing current upwardly toward the top of the blower chamber B¹. Any coarse material remaining in the current 85 may be deposited by centrifugal action in the trough Z as the current undulates to pass over it, and only the material which is light enough to float over the upper edge of the outermost deflector A¹ will then be 90 carried to the blower chamber B¹.

The air blown into the chamber B¹ descends therein, and diminishes in speed immediately below the outer deflector where the blower chamber has an enlarged portion C¹, below which the chamber has a contracting outlet D¹ toward which the current descends, so that dust escapes into the dust chamber G in a downward direction. Immediately inwardly of the annular passage C¹ is the return passage H which where it 95 communicates with the dust chamber is of relatively large area, and through which the current passes inwardly in transverse direction to its entrance to the dust chamber, so that the changing of direction of the current and the diminution of its speed, both tend to facilitate the separation of the dust floating in it, which settles in the dust chamber. 100

The current flowing through the return 105 passes over the upper open edge of the lower or tailings cone T and back into the suction chamber, through which it again rises, and from which it passes outwardly through the selector passages. 110

The internal selecting troughs W discharge at the bottom onto a cone E¹, and unless it is desired to separately collect material selected by them, they discharge this onto an upper receptacle or truncated cone F¹ which receives the discharge from the outer trough Z also, and conducts the discharge from both inwardly and drops it through its lower open end across the return duct and into the lower receptacle or tailings cone T. The coarse material from the distributing cones descends into the tailings cone, and thus the returning current traverses inwardly through both the selector tailings and through the distributor tail- 115 120 125 130

ings, and is enabled to float from either any dust therein fine enough to float with this current at its then speed.

The tailings cone T is vertically adjustable to control the current speed, being in the construction shown adjusted by the forked lever u operated by a screw v and wheel w. This cone slides vertically within guides x through a hub ring y which is carried by spokes z from the casing. The upper cones are positioned within the casing by adjustable spokes a¹, and suspended from the top by adjustable tie-rods b¹, and the intermediate deflectors and rings are carried 15 from the cone F¹ by braces e¹, c¹, d¹, f¹, g¹ and h¹ respectively, so that the annular discharge spaces between them are continuous and uninterrupted, thus affording opportunity for uniform outlet of material without 20 causing gaps through which excessive air current might flow.

Cross beams j¹ serve to stiffen the bracket f, and an outwardly flaring apron or cone k¹ reinforces the cone T and makes the dividing wall between the return chamber and dust chamber, and serves as the lower wall of the return passage. The apron k¹ is an annular valve or damper which may be secured to and movable with the cone T, but is 25 preferably sustained on this cone so that it can move with or either can be moved from the other, and the apron is sustained by the spokes z when the cone T is moved below it, and by the cone when the latter is moved 30 above the lowest position for the apron, both being guided by the vertical rods x in the construction shown. Thus the apron may serve as a damper for varying length of the vertical passages between the filter 35 troughs l¹ and the space through the return 40 passage H. The various rings or cones can be adjusted on their braces or otherwise to any relations desired so long as they are maintained concentric.

The various rings necessary to make the successive annular passages, the inner step by step distribution and retardation, and the changes in direction of current, as well as its variations in speed as it travels outwardly, may be formed and supported in any suitable way, according to the fineness desired for the final product, or the grade desired for the intermediate products which are selected out of the current by the selecting troughs.

In operation material enters through the hopper C and descends through the feed tube M onto the disk D. The speed of feed is regulated by adjusting the tube M toward 60 the disk. The disk centrifugally throws the material against the deflector N, from which it is deflected downwardly in an annular stream, so that the falling material resembles a tubular wall surrounding the suction 65 chamber O. As this material descends it is

collected by the upper ring Q, which retards its speed of descent and concentrates it on the ring R, which redistributes it on the next ring Q, and so on, until it falls on the lower ring or cone S, from which it falls to 70 the tailings cone T and escapes through the coarse outlet I.

The revolution of the blower causes an outward current from the suction chamber O to the blower chamber B¹, which current 75 flowing through the falling material carries outwardly the dust and smaller particles. The current opposite each annular passage is isolated from the next by an intermediate partition t of the blower, so that the falling 80 material is successively acted on by a series of independent currents. The outflowing current passes through the falling material radially and approximately horizontally, and is then directed upwardly over the collecting cone through the passage U, which 85 contracts the current to accelerate its speed and increase its carrying power, so that it may carry over the cone any particles that it has floated from the falling material. 90 Above the cone the direction of the passage U is suddenly changed by the deflector V, which directs the current downwardly toward the trough W, in which owing to the diameter of this trough being greater than 95 that of the preceding part of the passage U the speed of the current changes, so that its dust carrying ability is affected. The direction of the current in the trough W is again sharply changed upwardly by the deflector 100 X, and during this change of direction and accompanying variation of speed, the outflowing current is caused to drop in the trough W any pieces too large to be carried further. As the current rises up still higher 105 over the outer edge of the trough W it goes to the blower, through which it passes outward.

For many purposes the trough W alone will effect sufficient selection to give the desired fineness for the material settling in the dust chamber, but where an intermediate grade, or a further selection or greater fineness is desired, one or more additional troughs are provided, preferably outwardly 110 of the blower. The trough Z surrounding the blower is usually sufficient for the finest requirements. When this is used the current as it leaves the blower is directed outwardly in the trough Z by the blower F, and then again still further upwardly by the cone ring A¹, the action on the floated material being analogous in this case to that in the trough W, except that even a finer selection is made here. From the blower or 115 from the outer trough Z if used, the current rises toward the top b and curves downwardly through the chamber B¹, into the larger portion C¹ thereof, in which it expands and becomes less agitated, and through which 120 125 130

the fine material descends into the contracting outlet D^1 , from which it is discharged rapidly downwardly into the dust chamber G .

5 The particles separated out by the trough W sift through the narrow annular interstice between the deflectors V and X and drop through the current traversing the next succeeding passage until they descend onto the 10 cone E^1 . Thus should any dust escape from the current in an upper passage, it may be floated outwardly by the current in the succeeding passage, which while swift enough to float this dust, may not be swift enough to 15 float larger particles. The particles selected out in the outer trough Z will descend and be collected by the cone F^1 . As shown, both these products will be brought together and escape through the annular space between 20 the cones E^1 and F^1 and fall across the return current to the cone T . The escape passages between the cones for these selections are preferably sufficiently narrow to practically prevent escape of current through 25 them in either direction, and the lower cones E^1 and F^1 act substantially as a dam or partition across the lower edge of the blower, and should be arranged to substantially prevent direct return of air and to cause the 30 current to traverse through the dust chamber and the return passage to effect the desired operation.

The current will rise rapidly through the chamber O and distribute itself outwardly 35 through the suction passages, continually changing in direction and expanding and rising until it reaches the chamber B^1 . Its rapid descent from the latter will carry the dust floating with it downward. As its direction is changed toward the return passage 40 this will tend to throw out the dust centrifugally, and the relatively slow speed through the wide outer entrance or part of the return passage H will prevent the returning 45 current from floating back much dust, but while for many purposes the slow inward withdrawal of the returned air through the passage H transversely of its direction of flow through the chamber C^1 will sufficiently 50 free the returned air from floating dust, in some instances it is desirable to more completely eliminate floating dust in the returned current, and my invention provides for this and comprises an improved filter 55 or dust collector G^1 intermediate of the blower and return chambers and preferably surrounding the latter and enclosed by the former and adapted to be traversed by the inwardly flowing air and to extract floating 60 particles therefrom and conduct them across and below the path of the air current, and deliver them into the dust chamber or elsewhere as desired in case another grade consisting of this product is preferred.

65 Preferably this constitutes a foraminous

or interstitial wall intermediate of the blower and return chambers substantially cylindrically arranged around the latter and preferably stationary relatively to the adjustment thereof. Any suitable provision 70 for this may be employed according to my invention, but I preferably provide an improved filter G^1 comprising one or more series H^1 and I^1 of grooved or trough-shaped members. The outer series H^1 is composed of hollow semi-cylindrical vertical troughs 75 arranged side by side, spaced in parallelism, with the hollow faces toward the approaching current, and spaced apart to form current slots or passages m^1 intermediate of them, and the inner or second series I^1 is composed of similar members 80 similarly arranged at the lee side of the first series but staggered relatively thereto so as to bring their hollow sides opposite the air slots between the members of the preceding set. Any 85 number of series may be used, but a plurality is preferable and two series are usually sufficient for effectively filtering the fluid. These are preferably arranged vertically and 90 the apron or extension k^1 of the return cone T slides up within them as the cone is adjusted to regulate the flow.

The filter members may be of suitable 95 cross-section, better preferably semi-cylindrical, and as the current approaches them under the action of the suction within and the pressure without it forms dead spaces 100 or voids opposite their faces as it flows between their edges, permitting floating particles to contact with the concaved face and slide down within the hollow side of the member through the comparative current void there existing.

The current passing through the slots between the outer members is arrested by the hollow side of the succeeding inner member, which forms a similar void or dead space in which the particles may collect and descend while the current is divided and deflected laterally to each side of this member in order to pass it and reach the return chamber. The troughs are elongated in the direction of down-flow of the current 110 through the chamber C^1 , and open-ended, and vertical, so that they afford downward ways in which dust settling in them can descend into the dust chamber G without tendency to fall outwardly into the currents 115 or eddies in the chamber C^1 . When used they will be suitably arranged in the current passage to intercept and filter out and settle the material to be extracted, their arrangement in this instance being in concentric circular form because of the concentric disposition of the annular suction and discharge passages.

The frame f has a forked front opening z^1 , and the top b has a cover n^1 fitting the space between the beams j^1 , and the head L

of the fan comprises an outer ring σ^1 bolted on the hub or head p^1 which is separably connected to the tubular shaft K and to the ring σ^1 so that it can be separated and lifted 5 outwardly and forwardly between the beams to remove the shaft and distributing disc without disturbing the other parts.

The adjustment of feed by the feed tube M, and the speed of drive, having been determined, subsequent adjustment to control the current speed as desired will be made by raising or lowering the tailings cone T to diminish or increase the return passage 10 above it. The fine dust will be removed 15 through the outlet J and the coarse tailings through the outlet I, either continuously or otherwise as desired.

It will be seen that this invention provides improvements in apparatus for grading, sizing or selecting materials which can be variously and advantageously utilized for current separation, and it will be understood that the invention is not limited to 20 particular details of construction, arrangement or operation set forth as constituting its preferred form, since it can be employed in whole or in part according to such modifications as circumstances or the judgment of those skilled in the art may dictate, without departing from the spirit of the invention. 25

What I claim is:

1. In combination, a casing enclosing a chamber, a receptacle in said chamber having upper and lower openings communicating with said chamber, means for passing pulverulent material to be separated into said receptacle, means affording a way through said receptacle for the heavier particles of such material, means affording an endless current passage through and around said receptacle, means for circulating a fluid medium through said passage to carry off into said chamber the lighter particles of such material, and annular substantially vertically disposed foraminous filtering means across such passage and surrounding said way for intercepting particles carried by such medium, said filtering means being constructed and arranged to conduct the intercepted particles across and below the path of the medium and affording inwardly extending current passages for such medium. 50

2. In combination, a casing enclosing a chamber, a receptacle in said chamber having upper and lower openings communicating with said chamber, means for passing pulverulent material to be separated into said receptacle, means affording a way through said receptacle for the heavier particles of such material, means affording an endless current passage through and around said receptacle, means for circulating a fluid medium through said passage to carry off 55

into said chamber the lighter particles of such material, substantially vertically disposed foraminous filtering means across such passage and around said way for intercepting particles carried by such medium, said filtering means being constructed and arranged to conduct the intercepted particles across and below the path of the medium and affording inwardly extending current passages for such medium, and means concentric of said way for varying the space through which such medium is permitted to flow. 70

3. In combination, a casing enclosing a chamber, a receptacle within said casing having upper and lower openings communicating with said chamber, means for passing pulverulent material to be separated into said receptacle, means affording a way through said receptacle for the heavier particles of such material, means affording an endless current passage through and around said receptacle, means for circulating a fluid medium through said passage to carry off into said chamber the lighter particles of such material, substantially vertically disposed foraminous filtering means across said passage and surrounding said way for intercepting particles carried by such medium, said filtering means being constructed and arranged to conduct such intercepted particles across and below the path of such medium and affording inwardly extending current passages for such medium, and means surrounding said way for varying the space through which such medium is permitted to flow. 85

4. In combination, a casing enclosing a chamber, a receptacle in said chamber having upper and lower openings communicating with said chamber, means for passing pulverulent material to be separated into said receptacle, means affording a way through said receptacle for the heavier particles of such material, means affording an endless current passage through and around said receptacle, means for circulating a fluid medium through said passage to carry off into said chamber the lighter particles of such material, annular substantially vertically disposed foraminous filtering means across such passage and surrounding said way for intercepting particles carried by such medium, said filtering means being constructed and arranged to conduct the intercepted particles across and below the path of the medium and affording inwardly extending current passages for such medium, and means within said filtering means for varying the space through which such medium is permitted to flow. 100

5. In combination, a casing enclosing a chamber, an upper receptacle within said casing having upper and lower openings communicating with said chamber, means

for passing pulverulent material to be separated into said upper receptacle, a lower receptacle affording a way for the heavier particles of such material and having an open upper part affording communication between said chamber and said lower opening, means affording an endless current passage through and around said upper receptacle, means for circulating a fluid medium through said endless passage to carry off into said chamber the lighter particles of such material, and substantially vertically disposed foraminous filtering means across said passage and around said way for intercepting particles carried by such medium.

6. In combination, a casing enclosing a chamber, an upper receptacle within said casing having upper and lower openings communicating with said chamber, means for passing pulverulent material to be separated into said upper receptacle, a lower receptacle affording a way for the heavier particles of such material and having an open upper part affording communication between said chamber and said lower opening, means affording an endless current passage through and around said upper receptacle, means for circulating a fluid medium through said endless passage to carry off into said chamber the lighter particles of such material, substantially vertically disposed foraminous filtering means across said passage and around said way for intercepting particles carried by such medium, said filtering means being constructed and arranged to conduct such intercepted particles across and below the path of such medium, and affording inwardly extending current passages for such medium.

7. In combination, a casing enclosing a chamber, an upper receptacle within said casing having upper and lower openings communicating with said chamber, means for passing pulverulent material to be separated into said upper receptacle, a movable lower receptacle affording a way below said upper receptacle for the heavier particles of such material and having an open upper part affording communication between said chamber and said lower opening, means affording an endless current passage through and around said upper receptacle, means for circulating a fluid medium through said endless passage to carry off into said chamber the lighter particles of such material, and substantially vertically disposed foraminous filtering means across said passage and around such way for intercepting particles carried by such medium, said filtering means being constructed and arranged to conduct such intercepted particles across and below the path of such medium and affording horizontally extending current passages for such medium.

In witness whereof, I have hereunto signed my name in the presence of two subscribing witnesses.

GEORGE HOLT FRASER.
